YARN PACKAGE

Henry B. Cross, Jr., West Orange, N. J.

Application September 20, 1948, Serial No. 50,227

9 Claims. (Cl. 242—159)

1

This invention relates to packages of yarns or threads and more particularly to such packages for use in knitting, crocheting, tatting and the like.

The invention has particular application to packages of yarn or thread which are wound in a form similar to a cop or ball as a continuous strand of limited or predetermined length. Knitting and crocheting yarns commonly are prepared for use in the form of soft skeins or hanks from which the yarn may be wound in a ball in order that the yarn may be drawn therefrom conveniently and without tangling as the knitting or crocheting proceeds. It has been proposed heretofore also to prepare such yarns in the form sometimes referred to as "pull skeins" in which the strand is wound in a plurality of superposed layers with the inner end projecting from the package. The outer end is fastened upon the circumference of the package and the yarn as it is used is withdrawn at the inner end of the strand. Such a package is described in the patent to L. J. Barry No. 1,592,432, July 13, 1926. In this and similar packages prepared for knitting or similar operations the package has the soft and flexible character of the ordinary skein or hank of yarn.

In the preparation of such yarns for sale the skeins have been assembled in kits with supporting means of different types, in some cases in cardboard holders. In other cases so-called "bobbins" are provided in the kits on which the knitter may wind the yarn from the skeins. The length of the strand on each "bobbin" may be limited to that required for knitting a block or a plurality of blocks or fractions thereof of a yarn of given color or other characteristic in a predetermined pattern in the fabric. For knitting wool socks, sweaters and other garments with Argyle patterns, for example, the amount of yarn wound on each "bobbin" is small, the length of the strand ordinarily used varying between a few yards and 15 or 20 yards. Although greater lengths of the strand could be used in knitting many patterns, ordinarily longer lengths would make necessary packages of the yarn of a size and bulk which would cause inconvenience and interference in the hands of the knitter.

Such packages and the devices for holding them as heretofore used involve the winding of the required length of yarn on the "bobbin" which may be of cardboard or of plastic or other material providing the requisite stiffness to hold the yarn in place thereon. In the knitting of Argyle patterns these "bobbins" become suspended from

2

the fabric by looping a part of the end of the strand which has been knitted into the fabric about the bobbin or catching it on a notch in the bobbin. A plurality of such "bobbins" of the different colors of yarn used for the pattern are thus suspended from the fabric. The knitter picks up the "bobbin" and releases and unwinds from the "bobbin" such a length of the strand as is suitable for knitting the portion of the color in a row or other part of the color block as required for forming the pattern. It will be apparent that the use of "bobbins" requires that the knitter shall thus unwind the strand for each of the colors being knitted. The plurality of "bobbins" are additional to the weight of the yarn which must be suspended from the fabric in the hands of the knitter. Since they must have substantial dimensions the "bobbins" frequently interfere one with the other and with the selection of the proper "bobbin" from which the yarn of the requisite color and located in proper relation to the color block being knitted is to be unwound. The "bobbins" and the packing thereof increase the cost of preparation of the kit and require the time of the knitter for the winding operation, the yarn being thereby subjected to an additional handling operation.

It is an object of the invention to provide a yarn package which without the use of "bobbins" or other holders is suspensible by the inner end of the strand.

It is another object of the invention to provide a yarn package containing the required length of strand for knitting or otherwise forming predetermined patterns which requires no supporting means or "bobbin" and which may be suspended directly from the fabric being produced while providing also for easy withdrawal of the yarn as required.

It is a further object of the invention to provide a self supporting self suspending yarn package which has substantial resistance to flexure and elongation or other distortion.

It is an additional object of the invention to provide a self supporting and self suspensible yarn package for knitting or otherwise forming patterns of predetermined size in the fabric which retains its form without collapsing throughout the withdrawal of a greater part or substantially all of the length of the strand contained therein.

It is a feature of the yarn package of the invention that a continuous strand of the yarn is wound in a plurality of layers superposed one upon the other, these layers pressing inwardly

upon each other and upon the portion of strand adjacent the inner end thereof, that is the end of the strand at which the winding of the package is started. In the preferred embodiment of the invention the yarn package is in the form of a cartridge generally cylindrical with the superposed layers in contact with the inner end portion of the strand which extends generally along the axis of the cartridge. In the winding of the cartridge the operation is carried out without the use of a supporting tube, pinn or similar conventional supporting member so that as the winding starts and proceeds the layers are immediately wound upon and in contact with the inner end portion of the strand, these layers building up one upon the other until the requisite diameter of the package is obtained.

The package of preferred form may be wound on a Universal winder well known in the art to lay the strand substantially uniformly as a helix with the wraps of the strand in successive traverse of the thread guide in immediately juxtaposed relation to produce a uniform lay and a cylindrical form of the cartridge. In winding the cartridge of the invention the end may be fastened or wrapped directly upon the spindle of the Universal winder. The length of traverse of the thread guide of the winder with respect to the number of revolutions of the spindle ordinarily is maintained constant throughout the winding of the cartridge. As is usual in the winding of a package on a Universal winder the traverse over the length of the package is made during only a few revolutions of the spindle as will be understood from the drawings and the description of the invention which follows. The number of turns of the spindle may be of the degree of 2 to 4 during the traverse in one direction along the spindle. Successive wraps of the strand are laid in juxtaposition by virtue of the creep or gainage in the relation between the revolutions of the spindle and the operation of the traverse mechanism of the Universal winder, a slight additive or subtractive relation of the revolutions of the spindle to the linear movement of the thread guide being provided for and being adjustable to suit the different sizes of yarn being wound.

The invention provides a cartridge in which the strand of yarn is wound in this manner under substantial tension to produce the pressure of the superposed layers inwardly upon each other and upon the internal end portion of the strand. Initially and throughout a substantial part of the length of the strand contained in the package these superposed layers will press upon and grip this internal end portion as it is being withdrawn from the package and this gripping action is sufficient to make the cartridge suspensible by the internal end projecting from the cartridge at the axis thereof. Ordinarily yarns of worsted, cotton, nylon or other materials which are used in knitting and similar operations are capable of being wound on a Universal winder with a moderate tension without damage thereto either as to the strength of the yarn or undesirable change in its properties which provide the desired texture, feel and other characteristics in the fabric.

It has been found in accordance with the invention that worsted knitting yarn, for example, may be wound in a cartridge without a supporting core member and without a void at the axis of the cartridge with a tension which produces a compactness of the layers such that the gripping of the internal end by the superposed layers makes the cartridge suspensible by its internal end.

Initially and throughout a major portion of the length of the strand in the cartridge, as the inner end is withdrawn from the cartridge, because of the resilience of worsted knitting yarns, the inward pressure and the gripping of the internal end continues until the weight of the cartridge has been greatly reduced. The package thus continues to be suspensible. Moreover, even after the major central portion of the strand has been withdrawn from the cartridge, the pressure between the layers which has been produced in the winding of the yarn under tension serves to maintain such a degree of clinging contact of the remaining layers which are now of much reduced weight as to continue the suspensibility of the cartridge substantially until all of the strand is withdrawn from the cartridge. The uniform lay of the strand in the cartridge and the juxtaposition of the successive wraps of the strand wound on the Universal winder enhances this contact so that the suspensibility by the internal end continues for a cartridge of substantial size suitable, for example, for knitting Argyle patterns and the like.

The yarn package or cartridge of the invention thus formed without auxiliary supporting means or "bobbin" has a smooth exterior surface and there are no projections or edges such as are found in conventional "bobbins," which may catch in the yarns or in the fabric being knitted. Because of its compactness, the cartridge during withdrawal of the major portion of the strand therefrom has a considerable resistance to deformation, both bending and crushing, and to elongation. A plurality of such cartridges, therefore, may be suspended from the fabric in the requisite manner with such a length of the strand between the fabric and each cartridge as is convenient for the knitter. Because of the smooth, relatively long form of the cartridge of limited diameter and also because only the minimum cartridge and the fabric need be pulled out from length of the strand to extend between the cartridge, tangling of the different suspending strands and interference of the cartridge one with the other in the handling of the work piece in the knitting operation are minimized or entirely avoided. The continued gripping of the layers of the strand in the cartridge upon each other and upon the inner end portion of the strand enables this length suspending the cartridge to be adjusted by pulling out the strand to just the length required.

Other objects and features of the invention will be understood from the description of the drawing to follow in which:

Fig. 1 shows in elevation the cartridge of the invention wound on a Universal winder; and

Fig. 2 shows a top end view of the cartridge of Fig. 1.

In Fig. 1 the cartridge 1 of cylindrical form is shown with a strand of yarn 3 wound in helices thereon. In the particular embodiment of Fig. 1 four wraps 5, 7, 9 and 11 of the strand corresponding to three revolutions of the spindle are provided in the length of the cartridge. In the Universal wind the gainage or creep provided for in the drive between the spindle and the traverse mechanism of the thread guide insures that the successive wraps 13, 15, 17 and 19 are laid immediately adjacent the wraps 5, 7, 9 and 11. Depending on the size of the yarn a greater or less number of such successive wraps will be required to fill out the spaces between the wraps 5 and 7, 75 between the wraps 7 and 9 and between the wraps

9 and 11. In any case it is a characteristic of the Universal wind that these spaces are uniformly and closely filled with the successive wraps so that there are no humps or ridges due to superposed or crossed wraps and a substantially uniform cylindrical cartridge is produced.

The invention utilizes these features of the Universal wind to insure conditions which are favorable to securing the compactness of the package and the inwardly acting pressure and gripping of the stand adjacent the internal end 21 which projects from the upper end of the cartridge 1. While in starting the winding this inner end is wrapped about the spindle of the Universal winder it will be understood after the cartridge is removed from the spindle that the end 21 may be pulled out slightly and the portion 23 thereof will be positioned as shown in dotted lines in Fig. 1, that is, initially substantially straight along and at the axis of the cartridge 1. The tension maintained upon the strand 3 throughout the winding of the cartridge is such that the superposed layers of the strand press inwardly upon the subjacent layers and upon the internal end portion 23 to effect gripping of this end portion so that the cartridge 1 may be suspended by the end 21 as this end of the strand is withdrawn from the cartridge and knitted into the fabric.

Strands of worsted and other yarns have a substantial resilience when placed under tension which restores the strand when released from the tension to its original length. In winding such yarns in the cartridges of the invention advantage is taken of this characteristic to continue the requisite pressure of the superposed layers one upon the other and upon the internal end 23 which has been generally referred to above. In other words, as the core portion of the cartridge is removed the strand of the superposed layers contacts and squeezes down upon the inner end portion of the strand. This squeezing action will continue throughout the major portion of the length of the strand in the cartridge. Because of the characteristic of textile yarns made from fibre, such as wool, cotton and the like, from which fibre ends along the strand project somewhat there is a strong tendency of the yarn as wound in the cartridge for these fibre ends to entangle with the adjacent layers or with the adjacent wraps of the strand in the cartridge. This entangling contact serves to continue the suspension of the cartridge which is of much decreased weight when the core portion has been withdrawn until substantially all of the strand is withdrawn from the cartridge.

According to the invention it has been found that the tension under which worsted knitting yarns may be wound in a cartridge suitable for Argyle patterns may be such that the compactness or density of the cartridge is substantially in the range between 90 and 140 grains avoirdupois per cubic inch. Preferably for such worsted knitting yarns the compactness may be within the range between 120 and 130 grains per cubic inch.

The weight of the cartridge suitable for Argyle patterns preferably is not substantially greater than 145 grains. As a practical limit the minimum weight of the cartridge will be not substantially less than 10 grains. If a cartridge within these weight limits is wound with a compactness in the range above given, the cartridge will be suspensible by the inner end of the strand.

The diameter of such a cartridge suitable for

Argyle patterns of worsted knitting yarns may be substantially in the range between $\frac{1}{4}$ inch and $\frac{3}{4}$ inch and the length of the cartridge may be substantially within the range between 1 inch to 3 inches. These dimensions, however, may be varied with different yarns and for different purposes if the compactness as above described is provided.

As examples of the weight, dimensions and compactness of cartridges of practical size for knitting Argyle patterns with worsted knitting yarn, the following table is given:

Cartridge No.	Weight	Diameter	Length	Density
15		Gr. In.	In.	
#1	143	.690	2.94	140
#2	42.5	.485	2.125	127
#3	11	.335	1.375	122

The compactness or density is found by the following formula:

$$\frac{\text{No. of grains in cartridge}}{7854 \times d^2 \times l - .0274 \times l}$$

d =dia. of cartridge

l =length of cartridge

.0274 $\times l$ =cubic content of spindle having a diameter of $\frac{1}{16}$ inch.

30 The weights and measurements in the table were taken at 77° F. and 71% relative humidity.

In winding cartridges of worsted knitting yarn of the form above described on a Universal winder, a spindle having a diameter of between $\frac{3}{16}$ inch and $\frac{7}{16}$ inch may be used. While as small a spindle as possible is desirable, to reduce the void which must be closed by the squeeze of the superposed layers, and when the spindle is made of special steels the requisite stiffness may be secured with a smaller diameter, it is necessary or desirable to avoid such flexure of the spindle as will produce whipping during the winding operation and therefore uneven lay of the yarn and formation of the cartridge. A spindle of somewhat larger diameter within the range given may be used where the resilience of the yarn, as in worsted yarn, is capable of producing a substantial contraction and squeezing in of the superposed layers upon the inner layers and upon the inner end portion of the strand.

The ordinary range of yarn sizes of worsted knitting yarns is substantially between 4/4's and 2/20's. It has been found in accordance with the invention that yarns of different size and different plies substantially within this range may be wound in a cartridge having the dimension and weight substantially within the limits above given to produce compactness or density of the cartridge within the range 90 to 140. For the most part these yarns may be wound with a compactness in the preferred range of 120 to 130 to form cartridges which are suspensible by the internal end of the strand. It will be understood that the compactness in a cartridge required to be wound with only a relatively short length of the strand to suit the particular pattern, if desired, may be less than that of a cartridge in which the strand is required to be longer. With some sizes and types of yarns and depending somewhat on the sizes and plies and upon the character of the yarns and of the wool of which they are made, greater or less compactness or density may be used to avoid damage to the yarn due to excessive tension while at the same time securing the requisite squeezing action

of the superposed layers and the ultimate mutual contact of the outer layers to continue the suspensibility of the cartridge.

It has been found also in accordance with the invention that nylon yarn spun from "cut staple" and plied and twisted to have many of the characteristics of wool or worsted knitting yarns may be wound in cartridges with a compactness or density substantially within the same range as for worsted knitting yarns, namely, 90 to 140 grains avoirdupois per cubic inch to secure suspensibility. Such nylon yarns generally are made from 3 to 6 denier filament and of 2 to 4 ply. As an example, the following data are given with respect to a 2-ply nylon yarn of "cut staple" spun from 3 denier filament, this yarn being equivalent substantially to a 2/9's worsted system.

Cartridge No.	Weight	Diameter	Length	Density
#4	Gr. 35	.460	In. 2	126

This cartridge of nylon yarn has a compactness lying in the preferred range between 120 and 130 grains per cubic inch. Nylon yarns suitable for knitting spun from so-called "cut staple" have fibre ends projecting from the strand of the yarn as is the case with worsted yarns. Because of the existence of these fibre ends the surface characteristics of the nylon strand are such that a substantial friction and clinging is produced between the layers of the yarn in the cartridge. The contact of these layers upon the inner end portion of the strand may be continued during the reduction in the weight of the cartridge and substantially until the strand is fully unwound when the requisite compactness is provided in accordance with the invention. In general, the ranges of length, diameter and weight of the cartridge of nylon may be the same as with worsted yarns, but variation may be made in such dimensions of the cartridge of worsted, nylon and other yarns depending upon the character of the particular yarn, provided that the compactness is maintained substantially within the range given above.

It is desirable and may be important to avoid untwisting of the yarn as the strand is withdrawn from the cartridge by the knitter, especially when yarns such as worsted or nylon knitting yarns are used which are formed of a plurality of plies or constituent lineal elements twisted together to give strength, resilience and other characteristics of the yarn and the fabric made therefrom. It will be understood that, since the strand in the cartridge extends in helices about the axis of the cartridge, withdrawal of the strand at one end or the other of the cartridge will add to the twist originally given to the yarn or will subtract from this twist, that is, will twist or untwist the plies forming the strand of yarn depending upon the direction of the original twist in the strand, namely, left hand twist or right hand twist. As will be understood by those skilled in the art of winding yarns this may be accomplished by leaving the inner end of the strand projecting adjacent the tip or adjacent the base of the spindle of the winding machine when the winding is started, having regard to the direction of rotation of this spindle in relation to the direction of the twist in the yarn. By bringing out the end so that the withdrawal of the strand at its inner end from the center of the cartridge increases the twist no harm will be

done to the yarn because the increase of twist will merely tend to make the cartridge when suspended from the fabric turn reversely upon its axis as the strand is withdrawn, thereby to offset the increased twist. Untwisting of the strand on the contrary produces no increased force to turn the cartridge and to restore the initial twist. Such untwisting of the yarn therefore, may be harmful thereto.

10 While the invention has been described in connection with worsted and nylon yarns, within the scope thereof any yarns suitable for knitting and similar operations may be used which may be wound in a cartridge in the manner described and 15 with the requisite compactness and clinging contact of the superposed layers to secure the suspensibility of the cartridge. All such yarn packages are intended to be within the scope of the appended claims.

20 I claim:

1. A package of yarn in the form of a self supporting cartridge in which the yarn as a continuous strand is wound in a plurality of layers superposed one upon the other and upon and in contact with the inner end portion of said strand at the axis of the cartridge, the inner end of said strand projecting from one end of the cartridge at said axis thereof, the tension of the strand in said cartridge being sufficient to produce a compactness in grains per cubic inch substantially in the range between 120 and 130 to effect gripping of said inner end portion along said axis by said superposed layers in the cartridge to make said cartridge self suspending by said projecting 35 inner end throughout a substantial extent of the length of the strand as said inner end is withdrawn from the cartridge.

2. A package of worsted knitting yarn in the form of a cartridge without a supporting member 40 at the axis of the cartridge, the yarn in said cartridge being in a continuous strand wound in a plurality of layers with a substantially uniform lay in the several layers superposed one upon the other and superposed upon and in contact with 45 the inner end portion of said strand along the axis of said cartridge, the inner end of said strand projecting from one end of the cartridge at said axis thereof, the tension of the strand in said cartridge being sufficient to press the superposed layers upon the underlying layers and upon said inner end portion along the axis of the cartridge and the resilience of the strand in said layers maintaining the pressure upon said inner end portion throughout a substantial extent of the 55 length of the strand as said inner end is withdrawn from the cartridge, said cartridge having a weight not substantially greater than 145 grains.

3. A package of yarn in the form of a self-supporting cartridge in which the yarn as a continuous strand is wound in a plurality of layers superposed one upon the other and upon and in contact with the inner end portion of said strand, the inner end of said strand projecting from one 60 end of the cartridge at said axis thereof, said strand being wound in the package to provide a compactness in grains per cubic inch substantially in the range between 90 and 140.

4. A package of yarn in the form of a self supporting cartridge in which the yarn as a continuous strand is wound in a plurality of layers with a substantially uniform lay in the several layers superposed one upon the other and superposed upon and in contact with the inner end 75 portion of said strand along the axis of the car-

tridge, the inner end of said strand projecting from one end of the cartridge at said axis thereof, the length of said cartridge parallel to the axis being substantially in the range between one inch and three inches, the diameter of said cartridge being not substantially greater than $\frac{3}{4}$ inch, the compactness of said cartridge being substantially in the range between 90 and 140 grains per cubic inch.

5. A package of worsted knitting yarn in the form of a cartridge without a supporting member at the axis of the cartridge as defined in claim 2, the yarn size of said strand being substantially in a range between 4/4's and 2/20's.

6. A package of worsted knitting yarn in the form of a cartridge without a supporting member at the axis of the cartridge as defined in claim 2, the length of said cartridge being not substantially greater than three inches, the diameter of the cartridge being not substantially greater than $\frac{3}{4}$ inch, the yarn size of said strand being substantially in a range between 4/4's and 2/20's, the compactness of said cartridge being substantially in the range between 90 and 140 grains per cubic inch.

7. A package of yarn in the form of a self supporting cartridge in which the yarn as a continuous strand is wound in a plurality of layers with a substantially uniform lay in the several layers superposed one upon the other and superposed upon and in contact with the inner end portion of said strand along the axis of the cartridge, the inner end of said strand projecting from one end of the cartridge at said axis thereof, the tension of said strand in the cartridge being sufficient to compact the superposed layers of the strand to a compactness substantially in the range between 120 and 130 grains per cubic inch

to provide pressure of said superposed layers upon each other and upon said inner end portion sufficient to make said cartridge suspensible by said inner end as said inner end is withdrawn from the cartridge and to secure substantial resistance to flexure transversely of the axis of the cartridge.

8. A package of yarn in the form of a self-supporting cartridge as defined in claim 1, the strand of said yarn comprising cut staple nylon fibres.

10 9. A package of yarn in the form of a self-supporting cartridge in which the yarn as a continuous strand is wound in a plurality of layers superimposed one upon the other and upon and in contact with the inner end portion of said strand, the inner end of said strand projecting from one end of the cartridge at said axis thereof, the length of said cartridge being not substantially greater than three inches, the diameter of

15 20 the cartridge being not substantially greater than $\frac{3}{4}$ inch, the weight of the cartridge being substantially in the range between 35 grains and 145 grains.
